UNITED STATES PATENT OFFICE.

ROBERT KENT, OF BROOKLYN, NEW YORK.

IMPROVEMENT IN DEVICES FOR POINTING WIRE.

Specification forming part of Letters Patent No. 121,632, dated December 5, 1871.

To all whom it may concern:

Be it known that I, ROBERT KENT, of Brooklyn, in the county of Kings and State of New York, have invented a new and useful Improvement in Devices for Reducing or Pointing Wire preparatory to drawing it, and other purposes of which the following is a full, clear, and exact description, reference being had to the accompanying drawing forming part of this specification, and in which—

Figure 1 represents a front view of a device constructed in accordance with my improvement; and Fig. 2, a vertical section of the same at right angles to Fig. 1.

Similar letters of reference indicate corresponding parts.

My invention is mainly designed to be used as an attachment to the draw-bench in wire-drawing apparatus or devices; and consists in a combination of peculiarly constructed die-rollers geared together, for pointing the wire or reducing it at its end to facilitate the entry of the wire within the draw-plates.

Referring to the accompanying drawing, A represents a frame or bolsters for holding the pointing die-rollers B B, which are hung to work in suitable slotted bearings therein, and the upper one of which is held down to its place by adjusting-screws b b. These rollers are geared together by wheels C C, and capable of being turned as required by means of a lever, D, to provide for the adjustment of their reducing-grooves and retention of them when adjusted, as hereinafter described. Each roller has a partial groove, c, in its circumference, arranged to face or line with one another, and of a gradually-diminishing depth

and width from or near their one end toward their opposite end.

To point or reduce the end of the wire, the wire is introduced within the grooves c the requisite distance to secure the pointing of it, and the lever D worked so as to cause the grooved portions of the rollers to indent themselves within the wire, which is then drawn out from between the rollers, the lever D being simultaneously held to hold the rollers at their set on the wire. This points the wire so that it can be easily entered within or through the next smaller-sized hole in the draw-plate; and, after the wire has been drawn, it is again introduced at its end under a closer or smaller adjustment of the tapering grooves in the rollers within the latter by suitably turning them, and the pointing process repeated as before, to allow of the entry of the wire within the next-sized draw-plate of smaller gauge, and so on in succession for each draw of the wire, the rollers B B, by the construction of the grooves in them, answering, by repeated adjustment, to effect the same series or succession of reduced pointing operations as a sliding and fixed die provided with a multiplicity of grooves of different dimensions.

What I claim, and desire to secure by Letters Patent, is—

An adjustable wire-drawing machine, consisting of the rollers B, having grooves c of gradually-diminishing depth and width, geared together and provided with a holding-bar, D, for operation as herein described.

ROBERT KENT.
